United States Patent Office.

WILLIAM H. LANDBECK, OF ROCHESTER, NEW YORK.

Letters Patent No. 64,676, dated May 14, 1867.

IMPROVEMENT IN WRENCHES.

The Schedule referred to in these Letters Patent and making part of the same.

TO ALL WHOM IT MAY CONCERN:

Be it known that I, WILLIAM H. LANDBECK, of the city of Rochester, in the county of Monroe, and State of New York, have invented a new and useful Improvement on a Wrench, for which said wrench I received Letters Patent dated on the twenty-fourth day of April in the year of our Lord one thousand eight hundred and sixty-six; and I do hereby declare that the following is a full, clear, and exact description of the construction and operation of the same, reference being had to the annexed drawing, making a part of this specification, in which—

Figure 1 is a perspective view of my wrench showing my improvement thereon.

Figure 2 represents the connection and operation of my improvement.

Figure 3 represents connecting-plate F.

The object of my improvement is to do away with the thumb-projection α of my wrench already patented, and substitute an oblong plate, F, as shown in figs. 1, 2, and 3, (and hereafter to be described,) for the purpose of so connecting the ratchet-block S with the lever B as to enable any one using the wrench to disengage very easily the ratchet-block S with ratchet-lever A by opening the levers A and B, as shown by red lines in fig. 2, for the purpose of altering the space M, fig. 1. The oblong plate F is pivoted with a slot, β , on the one end, which is connected with lever B, and is held loosely, by means of screws $e e$, to the lever B and ratchet-block S, as shown in figs. 1 and 2. The slot β is for the purpose of giving more play to the lever or handle B. I further improve my wrench by adding a spring, E, shown in fig. 2, to the back part of my wrench, made fast at one end by a screw, n , on back part of block D, the other end of spring E resting on top of ratchet-block S, for the purpose of assisting in disengaging the ratchet-block S with the ratchet-lever A, as shown in fig. 2.

What I claim as my invention, and desire to secure by Letters Patent, is—

The oblong plate F and spring E, the whole arranged in the manner and for the purpose substantially as herein described.

WM. H. LANDBECK.
